FIG. 1

FIG. 2

FIG. 3

FIG. 4

FIG. 8

FIG. 5

FIG. 6

FIG. 7

FIG. 1 is a front elevational view of an agribuilding air intake embodying my new design.

FIG. 2 is an isometric view thereof.

FIG. 3 is a fragmentary rear elevational view thereof.

FIG. 4 is an end elevational view thereof showing the end opposite that shown in FIG. 2.

FIG. 5 is a sectional view taken in line 5-5 of FIG. 1.

FIG. 6 is a front elevational view of a second embodiment of the design of FIG. 1.

FIG. 7 is an isometric view of FIG. 6.

FIG. 8 is a sectional view taken in line 8-8 of FIG. 6.

FIG. 1,2,3,6, and 7 are broken away to indicate indeterminate length. All broken lines are for illustrative purposes only and do not form part of the claimed article.

This application is a continuation in part of my copending application Ser. No. 251,601, filed May 8, 1972, and

entitled Agribuilding Cooling Pad Plenum, now Pat. No. D232,310 granted Aug. 6, 1974.

I claim:

The ornamental design for an agribuilding air intake, as shown and described.
